UNITED STATES PATENT OFFICE.

BENJAMIN B. ENGLANDER, OF BROOKLYN, NEW YORK, ASSIGNOR TO ENGLANDER
SPRING BED COMPANY, OF BROOKLYN, NEW YORK.

SUPPORTING MEANS FOR HAMMOCKS.

1,357,282.

Specification of Letters Patent. Patented Nov. 2, 1920.

Application filed June 15, 1916. Serial No. 103,739.

To all whom it may concern:

Be it known that I, BENJAMIN B. ENGLANDER, a citizen of the United States, residing at Brooklyn, in the county of Kings and State of New York, have invented certain new and useful Improvements in Supporting Means for Hammocks, of which the following is a specification.

This invention relates to hammocks of that general class known as couch hammocks, it more particularly relating, however, to the means for supporting such hammocks, the object of the invention being to provide an improved means for supporting this style of hammock whereby the wear and tear on the canvas or fabric ends is avoided and the danger of tearing or ripping such canvas ends entirely eliminated, while the hammock is supported in a very efficient, simple and inexpensive manner.

A further object of this invention is the provision of improved supporting means for couch bed hammocks whereby the strain and weight will be not only carried directly by the supporting means and not by the fabric ends of the hammock as is the usual practice, but whereby also in one form thereof the hammock may have considerable resiliency or spring action, in addition to that which is usually present when the bottom thereof is made up of a woven fabric or springs.

In the drawings accompanying and forming a part of this specification, Figure 1 illustrates a hammock supporting tripod, and a couch hammock supported thereon by this improved supporting means, a part of the hammock bottom being broken away more clearly to illustrate the improvement; and Fig. 2 is an end view of one form of this hammock supporting means.

Similar characters of reference indicate corresponding parts in the several figures or the drawings.

The tripod 2 may be of any suitable form, and the hammock 3 comprises the usual bottom or seat 4 formed in any suitable way and usually comprising a metal spring upon which rests a suitable stuffed mattress or seat 4, the spring bottom being carried by suitable transverse angle irons 4' connected in any suitable manner. The hammock is provided with a folding back 5 having folding ends 6 which back and ends are usually of canvas or duck or any other suitable fabric and are reinforced at their upper

edges by end bars or spreaders 7, and by a rear or back spreader 8 having a hinge 9. The lower edges of the ends and back may be connected to the bottom in any suitable manner and are usually detachable therefrom, and for that purpose may be provided with suitable hooks or a hook carrying bar 9' to hook under the angle iron transverse bars 4' of the bottom.

The foregoing description is of a hammock well known on the market and therefore a more detailed description thereof is deemed unnecessary.

It has been the practice, however, to support hammocks of this general class by chains connected with the end spreader bars at the ends thereof so that the support for the bottom of the hammock consists solely of the canvas ends extending down from the spreader bars 7 to such bottom. The result has been that these canvas ends received the strain and weight of the occupants of the hammock and not only is there considerable wear and tear thereon, but they frequently tear under such weight, especially when the canvas has become weakened, owing to the action of the elements and frequent use. Not only this, but by reason of the fact that the supporting chains have been connected to the ends of the spreader bars 7 the weight on the structure frequently causes these bars to buckle, as the tendency of the supporting chains is to straighten into the shortest distance between the link at the top and the seat of the couch. The present improvement supports the hammock in such manner that not only may the hammock be removed from the supporting means quickly and readily, but the strain upon the canvas or fabric ends is entirely removed so that the hammock is supported directly at its bottom while at the same time the supporting means also maintains the canvas ends properly stretched, and the tendency of the end spreader bars to buckle is largely avoided.

In the present improvement a pair of supporting chains 10 are provided at each end supported in the usual manner by the tripod, which constitutes the fixed points of support. The lower ends of these supporting chains are provided with hooks 11 adapted to detachably pass into openings 12 inside of or back from the ends of each spreader bar 7 so that the most direct line of support 110

practicable is obtained. Detachably connected with these hooks 11 and extending downwardly therefrom are a pair of supplemental chains 13 hooked into the end supports or angle bars carrying the spring bottom or seat of the hammock, so that the hammock seat is supported directly from its bottom through the medium of the two sets of chains at each end, thus eliminating the weight and strain coming upon the canvas ends, while each pair of chains 10 maintains its fabric end extended upwardly into its proper position. By hooking the chains 10 into the spreader bar away from the ends thereof a more direct line of support is obtained than is possible where these chains are spread apart at their lower ends to connect with the ends of the spreader bars. It will be observed from the foregoing that the same hooks 11 which are connected with the spreader bars also carry the upper links of the lower set of chains so that as stated the entire strain of the seat is practically in a direct line from the tripod.

In order to give increased resiliency and spring action to the hammock the upper set of chains is provided with coil springs 20 located intermediate of their ends and this feature increases the comfort of the hammock materially.

I claim as my invention:—

1. A hammock having a bottom and fabric ends provided with spreader bars at their upper ends, two pair of cables at each end adapted to be suspended at their upper ends at their point of convergence from a point above the hammock and connected at their lower ends directly to the hammock bottom, the cables of each pair being directly connected together at one side of the face of the spreader bar and independently of said spreader bar, the upper cables of the two pair having hooks at their lower ends adapted to pass through openings in the spreader bar, the construction being such that the weight on the bottom is directly transmitted to and is carried by the upper cables and not by the fabric ends, and coiled springs located in the length of said upper cables.

2. A hammock having a bottom and fabric ends provided with spreader bars at their upper ends, two pair of cables at each end adapted to be suspended at their upper ends at their point of convergence from a point above the hammock and connected at their

lower ends directly to the hammock bottom, the upper cables of the two pair having at their lower ends coiled springs terminating in hooks adapted to pass through openings in the spreader bar and the lower cables of the two pair being connected directly to said hooks at one side of the face of the spreader bar and independently of said spreader bar, the construction being such that the weight on the bottom is directly transmitted to and is carried by the upper cables and not by the fabric ends.

3. A hammock having a bottom and fabric ends provided with spreader bars at their upper ends, two pair of cables at each end adapted to be suspended at their upper ends at their point of convergence from a point above the hammock and connected at their lower ends directly to the hammock bottom, the upper cables of the two pair having at their lower ends coiled springs terminating in hooks adapted to pass through openings in the spreader bar and the lower cables of the two pair being connected directly to said hooks at one side of the face of the spreader bar and independently of said spreader bar, the construction being such that the weight on the bottom is directly transmitted to and is carried by the upper cables and not by the fabric ends, said hooks having a detachable connection with the spreader bar away from the ends of said spreader bar, and the lower cables being located in substantial parallelism from the spreader bar to the bottom of the hammock.

4. A hammock having a bottom and fabric ends provided with spreader bars at their upper ends, two pair of cables at each end adapted to be suspended at their upper ends at their point of convergence from a point above the hammock and connected at their lower ends directly to the hammock bottom, means connecting the cables of each pair at one side of the face of the spreader bar and independently of said spreader bar and attachable to the side of the spreader bar whereby the weight on the bottom is directly transmitted to and is carried by the cables and not by the fabric ends or the spreader bar, and a coiled spring located in the length of each upper cable of each pair.

Signed at Brooklyn, in the county of Kings and State of New York, this 14th day of June, 1916.

BENJAMIN B. ENGLANDER.
